BED SPRING SUPPORT

Herbert V. Johnston, Modesto, Calif.

Application November 9, 1932, Serial No. 641,849

3 Claims. (Cl. 5—209)

This invention relates to a supporting member, or more specifically stated, to a device for engaging and supporting the spring frame upon which a mattress is placed.

Both wooden and so-called iron bedsteads are extensively used and, regardless of the material employed, a bed spring is usually placed between the side rails of the bed to form a resilient, yielding support for the mattress. In all instances some means must be employed for supporting the bed spring with relation to the side rails of the bed, and the most common practice is that of placing a series of wide wooden slats crosswise of the side rails to support the bed spring and the mattress placed on top thereof. Bed slats of this character are easily displaced, with danger to the occupant of the bed spring falling down, but more objectionable is the fact that slats of this character present surfaces of comparatively large area upon which dust accumulates to such an extent as to become insanitary.

The object of the present invention is to generally improve and simplify the construction and operation of bed spring supports; to provide a support which can be quickly and readily applied; to provide a support which is reversible so that no mistake can be made when placing the same in position; to provide supports which are adjustable to beds of varying width; to provide supports which cannot be displaced once they are inserted; and further, to provide supports which present such a small area that dust collection is substantially eliminated.

The support is shown by way of illustration in the accompanying drawing, in which—

Fig. 1 is a perspective view of a portion of a bed side rail and a spring frame showing the manner in which the support is applied.

Fig. 2 is a cross section of a bed showing the manner in which the supporting members are applied with relation to the bed spring and the side rails of the bed.

Fig. 3 is a perspective view of the support.

Referring to the drawing in detail, and particularly Fig. 3 which shows the bed spring support, it will be noted that the support consists of an elongated bar 2, in the upper surface of which is formed a series of notches 3—3. The notches are formed at the opposite ends of the bar and their function will hereinafter be described. Secured to opposite ends of the bars are angle iron members 4—4, these members being secured to the bar 2 by riveting, as indicated at 5, or any other suitable means.

The supports are applied to the side rails of a

bed and to the spring frame proper, as shown in Figs. 1 and 2. In these figures, A indicates the side rail of a bed and B the inner shoulder whereby the bed spring is supported. The bed spring proper usually consists of an angle iron frame C connected by cross slats D, the slats forming supports for the bed springs E and the tie wires F whereby they are secured with relation to each other.

In actual operation when the spring frame is placed between the side rails of a bed, the supporting members shown in Fig. 3 are inserted as follows: One angle iron member, such as shown at 4, is placed between two of the slats D of the spring frame with ends of the angle iron member, indicated at 6—6, resting on top of the respective slats. The bar 2 will in that position extend in under the angle iron frame C of the spring frame and one of the notches 3 will engage the lower edge thereof. The opposite angle iron member 4 will in this position engage the shoulder B formed on the inner surface of the side rail A and, as the weight of the bed spring is resting on the angle iron frame C, and this is, in turn, resting on one or another of the notches 3 of the bar 2 a rigid support is provided; longitudinal displacement of the support being prevented by engagement of the lower edge of the angle frame C with one or another of the notches 3. Longitudinal adjustment for varying width between the side rails A is obtained through the same means, and lateral displacement is prevented by cutting away a portion of the outer vertical ends of the angle iron members, as shown at 7—7. Shoulders are thus formed which engage between the cross slats D thereby securing the support against lateral movement. Two of the supports will usually be sufficient on each side of the bed but more or less may be provided as conditions may demand.

After the supports have been placed in position, it will be obvious that the spring frame, together with the mattress placed on top of the same, will be rigidly supported and secured. Any danger of any one of the supports being displaced or swinging out of position is entirely eliminated as each support is secured both against endwise and lateral movement. Collection of dust is reduced to a minimum as the surfaces presented by the supports are substantially nil, sanitation being thus insured. The supporting devices are exceedingly cheap to manufacture and they are easy to apply and no mistake can be made when applying the same, as both ends are the same thus permitting reversal thereof.

It is for this reason that the notches 3 are formed in opposite ends of the bar 2.

While certain features of the present invention are more or less specifically described, I wish it is understood that various changes may be resorted to within the scope of the appended claims. Similarly, that the materials and finish of the several parts employed may be such as the manufacturer may decide, or varying conditions or uses may 10 demand.

Having thus described my invention, what I claim and desire to secure by Letters Patent is—

1. The combination with a bed spring having a rigid frame and a plurality of slats extending 15 crosswise thereof, of a detachable member to support the bed spring with relation to the side rails of a bed, said member comprising a bar adapted to extend in under the rigid frame to engage and support the same, cross bars on opposite ends of the bar, one cross bar resting on the side rail of the bed and the other cross bar resting on the cross slats of the bed spring, means for securing the supporting member against end-

wise movement with relation to the rigid frame of the bed spring, and a shoulder at each end of each cross bar engageable with a pair of cross slats of the bed spring to secure the supporting members against lateral movement. 80

2. A bed spring support comprising an elongated bar, a cross bar at each end thereof, said cross bars being angle-shaped in cross section to present horizontal and vertical surfaces, and the ends of said vertical surfaces being cut away to form shoulders to secure the bed spring support against lateral movement with relation to the slats of a bed spring. 85

3. A bed spring support comprising an elongated bar and a cross bar fixed at each end thereof, said cross bars being angle shaped in cross section and similar in construction, whereby either will overlie two transverse slats of a bed spring while the other rests on the side rails of a bed 90 whereby the said elongated bar will form a support for the bed spring. 95
